UNITED STATES PATENT OFFICE.

PETER J. PALUTSKAS, OF PITTSBURGH, PENNSYLVANIA.

WINDOW-WASHING APPARATUS.

1,354,127.

Specification of Letters Patent. Patented Sept. 28, 1920.

Application filed July 20, 1918. Serial No. 245,812.

To all whom it may concern:

Be it known that I, PETER J. PALUTSKAS, a citizen of Russia, residing at Pittsburgh, county of Allegheny, and State of Pennsylvania, have invented certain new and useful Improvements in Window-Washing Apparatus, of which the following is a specification.

This invention relates to improvements in devices for washing windows and has as its special object the provision of means by which the outer surface of the window may be thoroughly washed in an effective manner and without leaning outward from the window.

A further object is to provide means which may be moved from side to side of the window frame and is operated from the inner side thereof in a convenient and rapid manner.

These and other like objects are attained by the novel construction and combination of parts hereinafter described and shown in the accompanying drawings, forming a material part of this disclosure, and in which:—

Figure 1 is a front elevational view of a window showing the manner in which the invention is used.

Fig. 2 is a vertical sectional view of the same, taken on line 2—2 of Fig. 1.

Fig. 3 is a fragmentary perspective view showing the apparatus in a partially extended position.

Fig. 4 is a fragmentary front elevational view showing a modified form of construction.

Fig. 5 is a transverse sectional view taken on line 5—5 of Fig. 4, and

Fig. 6 is a perspective view showing the applicator by which the cleansing is accomplished.

Referring to the drawings, the numeral 10 indicates the wall of the building having an opening containing an ordinary window frame 11, provided with vertical sliding sashes 12, containing transparent glass panes 13, the construction being in all respects of conventional type.

Adapted to rest upon the sill 14 of the window is a platform 15, on the upper surface of which is secured two rows of spaced pairs of lugs 16 and 17 respectively front and rear, in which, pivotally engaged upon the pins 18, are pairs of link connections 20 and 21, the same being engaged central of

their length by rods 22, connecting the several links on each side of the frame rigidly together in such manner that as they are moved to or from a common center, the front and rear row of links are co-incidently operated.

Engaged by pins 23 at the upper ends of the front links are crossed bars 24, joined at their point of intersection by pins 25, their outer upper ends being engaged by pins 26 with other bars 27, connected together at their converging points by a pivot 28, formed with an extending actuating handle 30, the arrangement being such that, as the handle 30 is raised or lowered, to cause the links 20 to approach or move away from a central median line therebetween, all of the several elements being arranged in pairs so that a substantially rigid construction is obtained.

Similarly connected, by the pins 31, in the rear row of links, 21, are bars 32, joined at their points of intersection by pins 33, and pivoted on other pins 34, with similar link connections 35, joined at their crossing points by a rod 36 and pivotally connected by pins 37 with pairs of upper links 38 by a rod 39, and engaged on the rod 39, between the pairs of links 38, is a vertical bar 40, containing a longitudinal slot 41, adapted to slide on the connecting rod 36.

Therefore as the handle 30 is raised or lowered, a corresponding movement is transmitted to the bar 40 in an obvious manner.

A block of felt 45, adapted to be saturated with the cleaning solution, is engaged with a plate 46, having attached upon the side opposite the felt a clip 47, engageable with the upper end of the bar 40 by means of a set screw 48, so that it may be adjusted 95 therewith. Thus as the handle 30 is actuated, the block will be correspondingly moved to an increased degree so as to traverse longitudinally upon the outer surface of the window pane 13.

In the modifications shown in Figs. 4 and 5 a similar base or platform 15 is used, having raised lugs 16, and links 20 engaged therein connected at their upper ends by the pins 23 with the outer links 24 in all respects 105 as before described.

The handle element however is omitted and in place thereof are engaged upon pins 50 a pair of links 51 and 52, the inner adjacent ends being connected with the stem of 110 a handle 54, which upon being raised or lowered, obviously causes the links 20 to

move upon the pivots 18, and through them, the upper elements in the manner before described, the arrangement of the actuating handle being preferably due to its convenience in manipulation.

Having thus described my invention and set forth the manner of its operation and use what I claim as new, and desire to secure by Letters Patent, is.

10 In a device of the character described, a base, a plurality of pairs of lugs secured on said base, two sets of pairwise arranged links, each set pivotally connected to two pairs of said lugs, pairwise arranged crossed

bars joined at their point of intersection 15 and pivotally secured to the links of each set, lower and upper cross bars for the rear set, rods connecting the two sets of links, a handle secured to the apex of the front set, rods connecting the upper crossed bars of 20 the rear set and a slotted vertical bar sliding on one of said rods and adapted to carry a wiper at its upper end, substantially as described and for the purpose set forth.

In testimony whereof I have affixed my 25 signature.

PETER J. PALUTSKAS.
